[57] CLAIM

The ornamental design for a wristwatch, as shown and described.

DESCRIPTION

FIG. 1 is a front elevational view of a wristwatch showing my new design;

FIG. 2 is a rear elevational view thereof;

FIG. 3 is a left side elevational view thereof;

FIG. 4 is a right side elevational view thereof;

FIG. 5 is an end elevational view thereof, the opposite end being a mirror image thereto.

The side opposite that shown in FIG. 5 is a mirror image of FIG. 5.
